GAME BOARD

Lorin Doral Winger, Bremerton, Wash.

Application December 23, 1953, Serial No. 28,191

Term of patent 3½ years

(Cl. D34—5)

To all whom it may concern:

Be it known that I, Lorin Doral Winger, a citizen of the United States, residing at Bremerton, in the county of Kitsap and State of Washington, have invented a new, original, and ornamental Design for a Game Board, of which the following is a specification, reference being had to the accompanying drawings, forming part thereof.

Fig. 1 is a top plan view of a game board showing my new design.

Fig. 2 is a sectional view taken on line 2—2 of Fig. 1.

I claim:

The ornamental design for a game board, substantially as shown.

LORIN DORAL WINGER.
